COMBINED WALL UNIT AND SEAT FOR A BATHTUB OR THE LIKE

Raymond Wallace Young, Louisville, Ky., assignor to
American Standard Inc., New York, N.Y.

Continuation-in-part of design application Ser. No. 18,369,
July 24, 1969. This application July 20, 1970, Ser.
No. 24,037

Term of patent 14 years

Int. Cl. D23—02
U.S. Cl. D23—69

FIG. 1

FIG. 3

FIG. 2

FIG. 1 is a front perspective view of the combined wall unit and seat for a bathtub or the like embodying my new design and showing the seat in its open position;

FIG. 2 is a front perspective view thereof showing the seat in its closed position; and

FIG. 3 is a longitudinal cross-sectional view taken on the line III—III of FIG. 2.

This is a continuation-in-part of design application Ser. No. 18,369, filed July 24, 1969.

I claim:

The ornamental design for a combined wall unit and seat for a bathtub or the like, substantially as shown and described.
